UNITED STATES PATENT OFFICE.

HAROLD DE FOREST ARNOLD, OF EAST ORANGE, NEW JERSEY, ASSIGNOR, BY MESNE ASSIGNMENTS, TO WESTERN ELECTRIC COMPANY, INCORPORATED, A CORPORATION OF NEW YORK.

POWER-LIMITING DEVICE.

14,585.

Specification of Reissued Letters Patent. Reissued Jan. 14, 1919.

Original No. 1,200,796, dated October 10, 1916, Serial No. 48,872, filed September 3, 1915. Application for reissue filed October 30, 1917. Serial No. 189,359.

To all whom it may concern:

Be it known that I, HAROLD DE FOREST ARNOLD, a citizen of the United States, residing at East Orange, in the county of Essex and State of New Jersey, have invented certain new and useful Improvements in Power-Limiting Devices, of which the following is a full, clear, concise, and exact description.

10 This invention relates to power limiting devices. Its object is to limit the power which may be transferred from a source of power to a receiving circuit, that is, to insure that no power in excess of a predetermined amount shall be transferred from the source of power to the receiving circuit. This object is accomplished by making use of the fact that an electric valve or unilaterally conducting resistance, when connected 15 in a circuit containing a battery or other source of electromotive force, said source being so poled as to tend to send current in the direction in which the valve will not pass electricity, acts as an infinite resistance. 20 to any impressed electromotive force in the opposite direction to, and less than that of said source. Such a polarized valve may, therefore, be placed as a shunt around a circuit to be protected, and will then short-circuit it for values of impressed voltage 25 higher than and in the opposite direction to that of the polarizing battery. However, such an arrangement will act only for impressed voltages in one direction; and to 30 secure protection against high voltages in either direction, it is necessary to add another element in shunt to the circuit to be protected and disposed in the opposite direction. In this case the circuit will be protected 35 against high voltages in either sense, and thus the current, and hence also the power which may be transferred to a receiving circuit of a given resistance, will be limited to the value which could be transferred by a driving electromotive force approximately equal to that of either polarizing battery. These unilaterally conducting elements should have low resistances in order to act as efficient short circuits, and it 40 has been found that thermionic devices are the most satisfactory for the protection of circuits used in signaling, to which class of circuits this device is intended to be ap-

plied. By a thermionic element is meant one consisting of a hot electron-emitting cathode and a cool anode in an evacuated vessel.

The application of this idea to alternating current circuits is shown in the drawing, in which 1 represents a generator or source of alternating current.

2 is one winding of a transformer of which 3 is the other winding, and 4 is one winding of a second transformer, whose other winding 5 is connected to the receiving device 6.

The structure next to be described is designed to limit the amount of power which can be transferred from the source 1 to the receiving device 6.

7 and 8 are thermionic elements, each consisting of an electron-emitting cathode 9 or 11, which may be heated in the usual manner, and an anode 10 or 12, each anode and cathode pair being inclosed in an evacuated vessel.

13 is a battery whose negative pole is connected to the anode 10, and 14 another battery whose negative pole is connected to the anode 12. The function of each of these batteries is to provide the polarizing electromotive force for each thermionic element. From the method of connection of batteries 13 and 14, and from the fact that the thermionic elements allow current flow only from anode to cathode, it will be apparent that with no impressed alternating voltage, no current can flow through either element. Current can flow through element 7, for example, only when the impressed voltage across the winding 3 is high enough to overcome the electromotive force of battery 13, in which case current will flow through this element from its anode to its cathode. The same remarks apply to element 8, except that in this case the impressed voltage across the winding 3 must be in the opposite direction to cause current to flow through that element.

From the foregoing discussion, it is apparent that neither element will permit the passage of current until the voltage across the transformer winding is larger than that of either battery. When the voltage is less than this, all the power generated by this source is transformed to the receiver 6; but

when this alternating voltage rises above that of the battery, some current is shunted around the receiver through the thermionic elements which, therefore, act as a short circuit on winding 4. If these elements are of low resistance, it will be clear that this short-circuiting effect may be made very efficient.

A spark-gap or arrester 15 is preferably connected as shown, its function being simply to provide additional protection to the circuit against extremely high voltages.

While the transformers used in this device are not absolutely essential, still they are desirable because by means of them the impedance relations of the network may be more efficiently adjusted. For example, if the thermionic elements have, as usual, a rather high resistance, more efficient operation will be secured if the transformer 2-3 is adapted to raise the voltage to be applied across the terminals. This stepping up of the voltage also insures more effective protection by means of the spark-gap 15. The transformer 4-5 would then be used to step the voltage down again to approximately its original value. Transformers are said to be arranged in "tandem" when, as here, the output terminals of one are connected directly to the input terminals of the other.

What I claim is:

1. In combination with a source of power and a receiving circuit, means for short-circuiting said circuit when the impulses from said source of power exceed a predetermined amount, comprising two unilaterally conducting elements connected in parallel and in opposition with respect to said source, and a source of electromotive force in series with each of said elements, said source of electromotive force tending to send currents in the directions in which said elements will not permit current flow.

45 2. In combination with a source of power and a receiving circuit, means for short-circuiting said circuit when the impulses from said source of power exceed a predetermined amount, comprising a unilaterally conducting element connected in parallel with said source, and a source of electromotive force in series with said element, said source of electromotive force tending to send current in the direction in which said element will not permit current flow.

55 3. In combination with a source of power and a receiving circuit, means for short-circuiting said circuit when the impulses from said source of power exceed a predetermined amount, comprising two unilaterally conducting thermionic elements connected in parallel and in opposition with respect to said source, and a source of electromotive force in series with each of said elements, said source of electromotive force

tending to send currents in the directions in which said elements will not permit current flow.

4. In combination with a source of power and a receiving circuit, means for short-circuiting said circuit when the impulses from said source of power exceed a predetermined amount, comprising a unilaterally conducting thermionic element connected in parallel with said source, and a source of electromotive force in series with each of said elements, said source of electromotive force tending to send current in the direction in which said element will not permit current flow.

5. A power-limiting device comprising two transformers connected in tandem, unilaterally conducting thermionic elements, said elements being oppositely connected across the winding terminals common to said transformers, and a source of electromotive force in series with each of said elements and tending to send current in the direction in which said elements will not permit current to flow.

6. In an electric system, the combination with a circuit, of means for applying electromotive force thereto, means in said circuit for preventing flow of current through the circuit in one direction at all values of applied electromotive force, and a source of direct electromotive force permitting flow of current through the circuit in the other direction when the applied electromotive force equals or exceeds a predetermined value and for preventing flow of current when the applied electromotive force is below said limiting value.

7. In an electric system, the combination with a line, of a shunt path therefor, means for applying electromotive force to said line, and means in said path for preventing flow of current through the path in one direction at all values of applied electromotive force, and for preventing flow of current through the path in the other direction when the electromotive force is below a predetermined value and for permitting flow of current when the electromotive force equals or exceeds that value.

8. In an electric system, the combination with a line, of means for applying electromotive force thereto, and a plurality of shunt paths for said line, each of said paths containing means for preventing flow of current through the path in one direction at all values of applied electromotive force and for preventing flow of current through the path in the other direction when the electromotive force is below a definite limiting value, and for permitting flow of current when the electromotive force equals or exceeds that value.

9. In an electric system, the combination with a line, of a plurality of shunt paths

- therefor, each of said paths containing means for preventing flow of current through the path in one direction at all values of applied electromotive force, and for preventing flow of current through the path in the other direction when the electromotive force is below a definite limiting value and for permitting the flow of current when the electromotive force equals or exceeds that value, said means in one of said paths being arranged in opposition to the corresponding means in another of said paths, and a transformer in parallel arrangement with said shunt paths.
- 10 15 10. In combination with a source of power and a receiving circuit, a power-limiting device comprising two unilaterally conducting thermionic elements connected in parallel and in opposition, a spark-gap in parallel with said elements, a source of electromotive force in series with each of said elements, said sources tending to send currents in the directions in which said elements will not permit current flow, and two transformers 20 25 with a winding of each connected across said parallel circuit, the other windings of said transformers being connected respectively to said source of power and to said receiving circuit.
- 20 25 30 11. In combination with a source of power and a receiving circuit, a power-limiting device comprising two unilaterally conducting elements connected in parallel and in opposition with respect to said source, a source of electromotive force in series with each 35 of said elements, said sources of electromotive force tending to send currents in the directions in which said elements will not permit current flow, and means associated with said device for transmitting current similar in wave form to the current received from said source of power.
12. In combination with a source of power and a receiving circuit, a power-limiting device comprising a unilaterally conducting element connected in parallel with said source, a source of electromotive force in series with said element, said source of electromotive force tending to send current in the direction in which said element will not permit current flow, and means associated with said device for transmitting current similar in wave form to the current received from said source of power.
13. The combination of a source of power, 50 a receiving circuit and a power-limiting device therebetween comprising a unilaterally conducting element, means tending to send current through said element in the direction in which current will not flow, and a connection between said device and said circuit whereby the latter transmits impulses similar in wave form to the impulses from said source.

In witness whereof, I hereunto subscribe my name this 6th day of October, 1917.

HAROLD DE FOREST ARNOLD.
